OF BERKELEY, CALIFORNIA.

TRACKER-VALVE MECHANISM.

1,186,759.

Specification of Letters Patent. Patented June 13, 1916.

Application filed March 13, 1915. Serial No. 14,180.

To all whom it may concern:

Be it known that I, GEORGE S. EARDLEY, a citizen of the United States, residing at Alameda, in the county of Alameda and State of California, have invented new and useful Improvements in Tracker-Valve Mechanism, of which the following is a specification.

This invention relates to a tracker valve mechanism for player pianos.

It is one of the objects of the present invention to provide means for adjusting the position of the tracker valve with relation to the music sheet as it passes over the tracker-board, and particularly to a mechanism which will permit the tracker valve to be adjusted while the music is being played.

Further objects will hereinafter more fully appear.

The invention consists of the parts and the construction and combination of parts as hereinafter more fully described and claimed, having reference to the accompanying drawings, in which—

Figure 1 is a front view showing the application of the invention. Fig. 2 is a plan view of the tracker valve. Fig. 3 is a section on line 3—3, Fig. 2. Fig. 4 is a view similar to Fig. 2, showing a slight modification of the adjusting mechanism.

Referring to the drawings, A indicates the tracker valve in general which is constructed as follows: 2 indicates an arm which is pivotally mounted, as at 3, on a plate bracket 4. Pivots on lugs 5 formed on said arm is a trip valve 6 which is normally held in closed position against the port 17 of the pneumatic mechanism by a coil spring 7. Straddling the outer end of arm

2 is a U-shaped clip 8 which is secured thereon by means of a screw 9. This screw extends through a pair of upturned lugs 10, formed on a second bracket 21, and a nut 11 mounted on the screw between the lugs forms a means by which the arm and trip valve may be adjusted with relation to the edge 12 of the music sheet 13. Beneath the lugs 5 the arm is formed with a lateral extension 23, slidably secured to the bracket 21.

In operation, referring to Fig. 1, 14 indicates a case in which the tracker-board 15 and reel 16 are mounted. The upper reel is adapted to be moved longitudinally in

the usual manner by means of the bellows 55 17 of the pneumatic mechanism and the connected tracker valve indicated at A for the purpose of keeping the perforations in the music sheet 13 in direct alignment with the openings 18 formed in the tracker-board. 60

In actual practice, it is found that different reels of music will vary slightly in width and will also in time become sufficiently worn on the edges to produce a tendency to run a little to one side or the other, 65 thus bringing the perforations in the music sheet out of alignment with the openings in the tracker-board. The tracker valve is provided for the purpose of automatically keeping the perforations in the music sheet 70 in alignment with the openings in the tracker-board. It is, however, necessary to adjust the position of the tracker valve to suit various reels. This is accomplished in the present instance by turning nut 11 in 75 one direction or the other. This causes arm 2, with connected trip valve 6, to swing about pivot 3 into or out of engagement with the edge 12 of the music sheet. The moment a reel has been placed in position 80 it is only necessary to turn nut 11 until the desired register is secured. The tracker valve will then automatically retain this register in the usual manner. In Fig. 4 the same result is accomplished by the use of 85 the screw 19 swiveled to bracket 22. The nut 20 is in this instance fixed or secured to the screw, while the screw passes through a threaded opening in arm 2. Any turning movement of the nut and screw will 90 thus cause the arm to swing about pivot 3 in one direction or the other or into or out of engagement with the edge of the music sheet.

The provision of the adjusting mechanism here provided permits the tracker valve to be quickly adjusted in connection with any reel inserted, and this adjusting mechanism may also be operated while the music is being played, as it is only necessary 95 to turn nut 11 in one direction or the other. The adjusting mechanism here provided is simple in construction and may be attached to any standard tracker valve now in use as it is only necessary to secure clip 8 to 100 the main swinging arm 2 upon which the tracker valve is mounted.

The materials and finish of the several

parts of the apparatus are such as the experience and judgment of the manufacturer may dictate.

I wish it understood that various changes in form, proportions and details of construction may be resorted to within the scope of the appended claims, and that I do not wish to limit myself to the specific design and construction here shown.

Having thus described my invention, what I claim and desire to secure by Letters Patent is—

1. A tracker valve mechanism comprising spaced brackets, an arm pivoted at one end to one of the brackets and slidably secured to the other bracket adjacent the opposite end, a port of the pneumatic mechanism of a piano-player carried by the arm adjacent the pivotal mounting, a tracker valve adapted for closing the port and pivotally carried by the arm adjacent the second bracket, the latter being provided with an upturned lug extending substantially parallel to the arm, and adjusting means interposed between and engaging with the arm and the lug of the second bracket for adjusting the arm and valve bodily.

2. A tracker valve mechanism comprising a bracket having an upturned lug extending transversely thereof, an arm consisting of a flat body having a lateral extension slidably secured to the bracket and a pair of spaced lugs, a port of the pneumatic

mechanism of a player-piano carried by the arm, a tracker valve for closing the port and consisting of a flat body formed with spaced ears pivotally secured to the lugs of the arm, said arm and valve extending transversely of the bracket and normally lying in parallel relation to each other, and a screw threaded member interposed between the bracket lug and arm for adjustably connecting the same.

3. The combination with the music sheet and tracker-board of a player-piano, of a bracket plate carried by the tracker-board, an arm pivotally mounted on the bracket plate, a port of the pneumatic mechanism of the player-piano carried by the arm, a trip valve pivotally mounted on the arm and normally closing the port, a U-shaped member embracing the outer end of the arm, a screw securing the member on the arm, a pair of lugs formed on the bracket through which said screw extends, and a nut on the screw mounted between the lugs, said lugs holding the nut against endwise movement while being turned.

In testimony whereof I have hereunto set my hand in the presence of two subscribing witnesses.

GEORGE S. EARDLEY.
